UNITED STATES PATENT OFFICE.

HARRY HAWES, OF NEW YORK, N. Y.

SEAT FOR RAILWAY-CARS.

SPECIFICATION forming part of Letters Patent No. 451,690, dated May 5, 1891.

Application filed January 16, 1890, Serial No. 837,123. (No model.)

To all whom it may concern:

Be it known that I, HARRY HAWES, of New York, in the county and State of New York, have invented a certain new and useful Improvement in Seats for Railway-Cars, of which the following is a specification.

My improvement relates particularly to means for shifting the backs of the seats of railway-cars from one edge of the seat to the other. This operation becomes necessary in order that the passengers may face the front of the car in whichever direction the car may be moving.

Figure 1 is a vertical section of a car-seat and means for shifting the backs of the seats, the section being taken on the line $x-x$, Fig. 2. Fig. 2 is a plan or top view of the same.

Similar letters of reference designate corresponding parts in both the figures.

20 A' designate seat-frames upon which a seat B is supported. The seat B may be of the usual or any desired kind.

C' designate swinging arms. In the example of my improvement shown said swinging arms are rigidly connected near their lower ends to a shaft D, which shaft is journaled near its ends in the seat-frames A'.

E' designate stationary arms for the car-seat. These arms are at the ends of the seat 30 and are provided with longitudinally-extending arc-shaped slots or grooves a. They may form part of the seat-frames. Upon the swinging arms C' and extending from the sides thereof are pins or projections a', which 35 pins or projections extend into the slots or grooves a. The arms C' are provided with transversely-extending arc-shaped slots or grooves c.

F designates a back for the seat. This back 40 is pivotally hung near its upper edge and at its ends in the upper end portions of the swinging arms C'. Near the lower edge of said back and extending from the ends thereof are pins or projections f, which pins or projections extend into the arc-shaped slots or 45 grooves c in the arms C'. The ends of the slots or grooves a operate as stops to limit the degree of swinging movement which may be imparted to the arms C'. The ends of the 50 slots or grooves c operate as stops to limit the degree of swinging movement of the back F.

The degree of swing of the arms C' and of the back F is such that when the back has been brought into either of its positions it will stand at a proper angle to form an easy 55 support for the back of a person occupying the seat. I have shown the ends of the slots or grooves a as provided with bumpers b, which bumpers may be made of india-rubber. They prevent noise and too violent striking 60 of the pins or projections a' against the ends of the slots or grooves a.

The means for shifting the backs of all the seats along one side of the car in unison consists of a shaft G, upon which shaft are mounted a number of worms g, which worms will correspond in number to the number of seat-backs to be shifted. These worms engage worm-wheels G', which worm-wheels are rigidly keyed upon the shafts D. Rotary motion 65 imparted to the shaft G will thus cause the swinging of all the arms C' and the backs F in the row of seats. As an advantageous means for rotating the shaft G, I provide one end of the shaft with a bevel gear-wheel H, 70 which gear-wheel gears with another gear-wheel H', to the rear side of which is secured a toothed wheel H². The gear-wheel H' and the toothed wheel H² are mounted upon a stud h, extending from the side of the car. 75 Upon this stud is hung a lever I, near the lower end of the latter. Upon the lever I is arranged a sliding locking-tooth I². The locking-tooth I² is connected by means of a rod i to a lever J, fulcrumed upon the lever I near 80 the upper end of the latter. The lever J comprises a handle j, near the handle of the lever I. By grasping the handle of the lever I and forcing the handle of the lever J toward it the sliding tooth I² may be withdrawn from between the teeth on the toothed wheel H². The lever I may be then swung into a desired position upon either side and the sliding tooth I² passed into a space between the teeth upon the wheel H². By then swinging the lever I 85 in the required direction rotary motion may be imparted to the wheel H², so as to transmit rotary motion to the shaft G. Thus the arms C' and the backs F may be shifted to either of their positions, as required. When the 90 backs have been shifted to their required positions, the worms g and the gear-wheels G'

operate as locks to prevent the swinging of the arms C C' without rotating the shaft G.

Of course, if the swinging arms C C' were provided with the slots or grooves *a* and the stationary arms E E' were provided with the pins or projections *a'*, the effect would be the same. Likewise, if the swinging arms C C' were provided with the pins or projections *f*, while the backs F were provided with slots or grooves *c*, the result would be the same.

What I claim as my invention, and desire to secure by Letters Patent, is—

The combination, with a number of seat-

frames and seats, of swinging arms pivoted near their lower ends to the seat-frames, seat-backs suspended from the swinging arms, pinions fixed to the swinging arms, and a rotary shaft provided with worms in engagement with the said pinions for simultaneously shifting the swinging arms and backs, substantially as set forth.

HARRY HAWES.
